United States Patent Office

Des. 231,413
Patented Apr. 16, 1974

231,413

MAGNETIC CIGARETTE HOLDER

Peter Sopuch, 2815 Charter Blvd.,
Troy, Mich. 48084

Filed Oct. 20, 1971, Ser. No. 191,137

Term of patent 14 years

Int. Cl. D27—02

U.S. Cl. D85—8 B

FIG. 1

FIG. 2

FIG. 3

FIG. 4

FIG. 5

FIG. 1 is a perspective view of a magnetic cigarette holder showing my new design;

FIG. 2 is a side elevational view, the opposite side being substantially a mirror image thereof;

FIG. 3 is a side elevational view at 90 degrees to FIG. 2, the opposite side being substantially a mirror image thereof;

FIG. 4 is a top plan view; and

FIG. 5 is a bottom plan view thereof.

I claim:

The ornamental design for a magnetic cigarette holder, as shown.
